PERPETUAL CALENDAR

Wilfred E. Thibodeau, Falls Church, Va.

Application August 1, 1957, Serial No. 675,741

8 Claims. (Cl. 40—113)

(Granted under Title 35, U.S. Code (1952), sec. 266)

The invention described in the specification and claims may be manufactured and used by or for the Government for governmental purposes without the payment to me of any royalty thereon.

This invention relates to calendars, and in particular to a type known as a perpetual calendar both in the sense of being settable at any date and in the sense of being a finder of the day of the week corresponding to any given date.

The cyclic rhythm of calendar data follows a definite formula which has been known and employed for centuries, and many forms of perpetual calendars or finders have been proposed heretofore. However, none of these has ever come into appreciable use either because their employment has necessarily involved certain degrees of mental effort and were therefore divorced from the simplicity demanded by public fancy, or the proposed devices were too cumbersome or expensive for popular appeal.

For instance, Patent No. 2,215,020 employs several sets of tables which must be referred to in sequence, and the process involves mental addition. Furthermore, this device purports to aid the user by distinctive marking of each 4th year of a century but does not make such provision for those years ending in 00 which are not leap years. It is noteworthy that the patentee himself suffered from this defect when in giving an example of a date in the year 1900 he considered it a leap year, which it was not. In my device this cannot happen.

The device of Patent No. 1,585,470 has commendable features, but suffers from the defect that the months, days, centuries and years are arranged in groups which do not present an orderly sequence, and therefore involves hunting for the data. This device also leaves the burden of detecting leap years to the operator.

In the present invention I have provided a calendar which involves no mental effort other than to select and arrange the components of a date from an arrangement occurring in orderly sequence and to perform an operation similar to the dialing of a telephone. No mental arithmetic or reference to tables is required and even the data peculiar to leap years, including the operation of determining whether a given year is a leap year are automatically taken care of.

It is therefore an object of the invention to provide a calendar which indicates days of the week for given dates with a minimum of mental effort on the part of the operator. A further object is to provide a calendar which automatically accounts for leap year data. Yet another object is to provide a calendar as aforesaid which is simple and inexpensive in construction and simple and reliable in operation with a minimum of data hunting.

These and other objects are attained by the invention which may be briefly described, in principle, as follows:

The basic formula for days of the week depends upon a cyclic movement through groups of seven. This is affected by the particular month, the day of the month, the number of the century and the year of the century. A

2

perpetual calendar in any form will involve these four data and will have further involvements in the effect of leap years and in the determination as to which years are leap years. The formula is precise, however, and the computation can easily be done entirely mentally for any given date. For instance, an index number is associated with each month in the following manner:

10	Jan.	Feb.	Mar.	Apr.	May	Jun.	Jul.	Aug.	Sep.	Oct.	Nov.	Dec.
	0	3	3	6	1	4	6	2	5	0	3	5

If the year is a leap year the numbers for Jan. and Feb. are as follows:

15

Jan.	Feb.
6	2

These numbers, as associated with the months, may be easily committed to memory.

The second piece of data is the cardinal number representing the day of the month.

25 The third piece of data is the century index, associated with the two digits indicating the century, and these indices are as follows, in a definite cyclic pattern

30

16 20 24 etc. 0	17 21 25 etc. 5	18 22 26 etc. 3	19 23 27 etc. 1

35 The fourth piece of data is obtained from the year of the century, by multiplying it by $5/4$ and ignoring the remainder, if any.

The four items of data are summarized as follows:

M =the month index

40 D =the day of the month

C =the century index

$Y=5/4$ of the year of the century, neglecting remainder.

If you add $M+D+C+Y$ and divide by 7, the remainder is the number of the day of the week, counting Sunday as the first day of the week. In order to perform the operation mentally I have found it convenient to avoid large numbers in the addition by casting out 7's as they occur. For example, take the date April 24, 1904. It is first noted that this is a leap year, but the month is neither Jan. nor Feb. so no correction on account of leap year is necessary.

The number for April is 6

Casting 7's out of 24 leaves 3

55 The total thus far is $6+3=9$ and casting out the 7 leaves 2. The number for the 1900's is 1 which added to 2 gives 3. $5/4$ of 04 is 5 which added to 3 gives 8. Casting 7 out of 8 leaves 1 and the answer is Sunday.

60 As a further example take July 4, 1776.

The number for July is 6

4, being less than 7, is added to 6, totalling 10

Casting out 7 leaves 3

The number for the 1700's is 5, which added to 3 totals 8

65 Casting out 7 leaves 1

$5/4$ of 76=95 which added to 1 totals 96

Casting out 91 as a multiple of 7 leaves 5

The day of the week was, therefore, Thursday.

70 In the embodiment of the invention shown in the accompanying drawings and described in the specification to follow, I have arranged the four components of the dates

in normal sequence and associated with each component the data according to the above general formula, but in which the 7's have already been cast out. The separate data then range from 1 to 6 and when added may involve a further casting out of 7's which I achieve automatically by dialing the data numbers consecutively in continuous, clockwise motion on a seven place dial, after setting it at a zero or reference position.

In the drawings:

Fig. 1 is a top plan view of the full assembly,

Fig. 2 is a diametral section taken horizontally on Fig. 1,

Fig. 3 is a sectional view taken on the line 3—3 of Fig. 2,

Fig. 4 is a top plan view of one component of the assembly, and

Fig. 5 is a fragmentary view of a detail showing the ratchet arrangement.

Referring now to the drawings by characters of reference there is shown a shallow cylindrical container 1 having a bottom 2 and snugly and rotatably receiving a disc 3. Disc 3 has a central cylindrical cavity receiving a second disc 4 rotatable in the cavity and having a top surface flush with that of disc 3. Disc 4 has two concentric, annular channels one of which mounts an annulus 5 and another of which mounts an annulus 6, and has a central cylindrical cavity mounting a disc 7, annuli 5 and 6 and disc 7 being rotatable in their mountings.

As seen in Fig. 3, disc 3 carries the years of the century from 00 to 99 fanwise in numerical order, and diametrically opposite each year on the disc 3, but in a separate annular region, is its associated code number. For instance, opposite 57 is the number 1, and opposite 04 is the number 5. The code numbers are inverted with respect to their associated data, since, as will be seen, they will be read at the left of the assembly, while the date will be set at the right.

Disc 4 carries the century numbers, herein shown only from 16 to 24, and diametrically opposite each is its code number. For instance, opposite 16 is a blank, and 1 is opposite 19.

Annulus 5 carries the days of the month from 1 to 31 in regular order, and diametrically opposite each is the code number, computed as the remainder above the highest multiple of 7 in the day of the month. For instance, opposite 24 is the number 3 and opposite 28 there appears no number at all.

Annulus 6 carries the months, and diametrically opposite each is its code number. For instance, opposite June is the number 4. Opposite Jan. and Oct. no number appears since it is not necessary to dial 0.

It will be noted that annulus 6 is somewhat wider than members 3, 4 and 5, the reason being that provision is here made for leap year adjustments. As noted above the index for Jan. or Feb. is reduced by 1 in a leap year. The corrections are involved only in Jan. and Feb. because the basic formula makes a correction which applies from the beginning of a leap year whereas the shift does not actually take place until the last day of Feb. has been passed. The same result can be achieved by adding 6, and therefore on the year-of-the-century disc 3 the code number 6 is placed radially opposite each year divisible by 4, except the year 00, on a circular line underlying the month disc 6, the numerals 6 appearing as dotted lines in Fig. 3. Opposite the year 00 a code numeral 6 also appears on disc 3 underlying disc 6 but located radially inward of the line of the balance of the 6's. Since these 6's are to be used only in the case of Jan. or Feb. access to them is accordingly limited by a sector-shaped opening 12 in the month disc 6. Since access must be had for any of the century years, this is provided by an arcuate through opening 14 in the century disc 4, opposite and equal in extent to the span of the century years. Also, since the single 6 opposite the year 00 is to appear only in connection with the century years divisible by 4,

namely 16, 20 and 24, access to this 6 is limited by a series of through openings 16, radially aligned with said century years. It will be seen that the years divisible by 4 except 00 will produce the number 6, any century will pass it through arcuate slot 14 and Jan. or Feb. will permit its viewing through sector 12. Similarly, the year 00 will produce a 6, but only the centuries beginning with 16, 20, or 24, will permit its viewing through openings 16, and only Jan. or Feb. will permit its viewing through sector 12. This takes account of the complete rule for determining leap years and the computation is built into the machine itself and requires no mental effort.

For convenience and abatement of possible confusion I have provided, as seen in Fig. 1, a mask consisting of annuli 17, 18 and 19 connected by bridges 19, 20, 21 and 22 the purpose of the mask being to cover the dialing code numbers but leave exposed the date components for ready finding and arrangement. In bridges 21, 22 are provided a series of three windows, 23, 24, 25 in which the date considered may conveniently be framed, either for finding purposes or day to day use as a calendar. The window 23 will frame the month, window 24 the day of the month and window 25 the century and century year. Preferably in manufacture, the mask will be rendered integral with the container 1.

In the region of bridges 19 and 20 is a series of openings 26, 27, 28, 29 which will expose the respective dialing code numbers antipodally disposed with respect to the respective date components appearing in windows 23, 24, 25, and the further openings 30 and 31 which provide access to the additional code numbers pertaining to leap years when they appear through sector 11.

The dialing disc 7 has seven openings 32 equally spaced on a circular line which may be engaged by a pencil or other instrument for ease of dialing. The inner annulus 19 of the mask has, around its inner periphery, the numbers 1 to 6 equiangularly spaced on 6 of seven stations, the 7th being left blank and carrying a projection 33 serving as a stop means for the dialing pencil.

To prevent back-dialing a ratchet device may be employed such as spring finger 34 attached to disc 4 engaging in any of 7 recesses 35 in the underside of disc 7. The days of the week are indicated on dial 7, but are concealed by annulus 19 of the mask except when appearing under a window 36 therein. With the formula employed, Saturday, the seventh day of the week is the zero reference or starting point for dialing and, to accentuate this, distinctive marking such as a prominent circle 37 around one of the openings 32 is provided, which must be dialed first before the other data are dialed.

For convenience in setting up the date, openings 38 for engagement by a pencil may be provided above each date component on the discs and annuli, and slots 39 are provided in bridges 21, 22 to accommodate the pencil.

The invention may now be illustrated by way of example, for which the date July 4, 1863 is selected. The date may be set in any order but with the embodiment shown it is desirable to move discs 3 and 4 first because the annuli ride in these. The year 63 is readily located in the sequence of numbers on disc 3 and moved into position in window 25. On the opposite side of the instrument the code number 1 then appears in opening 26. In the same manner the century year 18 is easily located on disc 4 and moved into position in window 25 alongside the number 63 to provide the complete number 1863.

Opposite 18 on disc 4 the associated code number 3 then appears in opening 27. Next annulus 5 is rotated to bring the number 4 into window 24 and on the opposite side of the annulus the code number 4 appears in opening 28. Next July is moved into place in window completing the display of the date, and the associated July code number, 6, appears in opening 29. Nothing appears in openings 30 and 31 because 1863 was not a leap year.

To recapitulate, the dialing code numbers 1, 3, 4 and 6 now appear in openings 26, 27, 28 and 29. The dial is

now zeroed to bring Sat. into view by dialing the position of circle 37 to the stop 33. Then the disc 7 is dialed in succession from the numbers 1, 3, 4 and 6 to the stop means, after which the proper day of the week for the date shown will appear in window 36, and the final day at Gettysburg is found to have been a Saturday.

While a particular embodiment of the invention has been shown and described it is not to be deemed as limited thereby. For instance, whereas I have shown a combination of discs and nested annuli the entire assembly could as well comprise a system wholly made up of superimposed discs of regularly decreasing diameter, however this would render more involved the access to leap year data.

Broadly the invention contemplates a system in which the input data are arranged in orderly fashion for ready location and associated numbers are arranged for automatic exposure along with the display of the date components, and an adding means is provided for further reducing the said associated numbers by casting out each total of seven as it occurs. The invention also includes the feature of completely automatic corrections for leap years.

It is not necessary that the code numbers be antipodally arranged with respect to the date components, since these may be located at any convenient angle from the reference data and may even be closely adjacent the same. It is even possible for the code numbers to be displaced at different angular distances on the respective discs and annuli.

As shown, the device applies to dates on the Gregorian calendar, which is now in use. However, any date can be analyzed with respect to the Julian calendar by the simple device of dialing one additional code number of fixed value for all cases.

The structure and operation of the device is such that the operations of zeroing the dial and dialing the code numbers may be carried out repeatedly, and thus the accuracy of the day of the week shown may be checked at all times, as for instance if there is a suspicion that it has been disturbed from proper setting.

It is also worth noting that the device may be used to check the day of the month if the day of the week is known. In this case one dialing will verify a correct guess, or indicate a difference from which the result may be inferred, and this may then be given a final dialing check, if desired.

While I have shown and described a particular embodiment of my invention, the same is not limited thereby but may partake of various forms and comprise equivalents obvious to those skilled in the art, and therefore, the invention should not be deemed as limited except as shall appear from the spirit and scope of the appended claims.

I claim:

1. A calendar device comprising movable members bearing, respectively, date components representing the months of the year, cardinal numbers representing the days of the month, the first two digits of the year number and the last two digits of the year number, code numbers from 1 to 6 and including blanks, on each member, fixedly associated with the respective date components thereon, and means carried by the said device to produce the cumulative sum of a set of said code numbers, above the highest multiple of seven corresponding to a set of said components representing a given date, as arranged by movement of said members, said means comprising a dialing disc having seven, equiangularly spaced stations, and index means for said dialing disc, said index means comprising seven equiangularly spaced stations, six of which are numbered from 1 to 6, and said dialing disc bearing the respective days of the week arranged for cyclic accumulation in correspondence with the accumulation of said code numbers.

2. A calendar device comprising movable, coaxial, cir-

cular members bearing, respectively, in normal sequence date components representing the months of the year, cardinal numbers representing the days of the month, the first two digits of the year number and the last two digits of the year number, code numbers from 1 to 6 and including blanks, on each member, fixedly associated with the respective date components thereon, indicator means for rendering prominent a set of said code numbers corresponding to a set of said components representing a given date, as arranged by movement of said members, and means carried by the said device to produce the cumulative sum of said set of code numbers above the highest multiple of seven, said means bearing the days of the week arranged for cyclic movement in unison with the numbers being accumulated.

3. A calendar device comprising movable, coaxial, circular members bearing, respectively, in normal sequence, date components representing the months of the year, cardinal numbers representing the days of the month, the first two digits of the year number and the last two digits of the year number, code numbers from 1 to 6 and including blanks, on each member fixedly associated with the respective date components thereon, indicator means for rendering prominent a set of said code numbers corresponding to a set of said components representing a given date, as arranged by movement of said members, and circular means carried by the said device to produce the cumulative sum of said set of code numbers above the highest multiple of seven, said circular means bearing the days of the week arranged for cyclic movement in unison with the numbers being accumulated, said means comprising a coaxial dialing disc having seven, equiangularly spaced stations, and index means for said dialing disc having seven equiangularly spaced stations, six of which are numbered from 1 to 6.

4. A calendar device comprising movable members bearing, respectively, date components representing the months of the year, cardinal numbers representing the days of the month, the first two digits of the year number and the last two digits of the year number, code numbers on each member fixedly associated with the respective date components thereon, indicator means for rendering prominent a set of said code numbers corresponding to a set of said components representing a given date, and means carried by said device to produce through cycles having a periodicity of seven the cumulative sum, above the highest multiple of seven of a set of said code numbers corresponding to a set of said components representing a given date, as arranged by movement of said members, said latter means bearing the days of the week arranged for cyclic movement in unison with the numbers being accumulated, the code numbers associated with the year numbers including numbers associated only with leap years, said latter numbers being manifest through said indicator means only in the cases where the selected date component comprises January or February, and either the year of the century, exclusive of double zero, is divisible by four, or the years ending in double zero are divisible by four hundred.

5. A calendar device comprising a plurality of circular members arranged for rotation about a common center, a first one of said members bearing the year numbers 00 to 99 arranged in numerical order at a fixed radial distance and code numbers arranged in correspondence with the respective said year numbers, a second one of said members bearing century numbers arranged in numerical order at a fixed, radial distance and code numbers arranged in correspondence with the respective, said century numbers, a third one of said members bearing the day-of-the-month numbers 1 to 31 arranged in numerical order at a fixed, radial distance and code numbers arranged in correspondence with the respective, said day-of-the-month number, a fourth one of said members bearing the names of the months, in order, at a fixed, radial distance and code numbers arranged in correspondence

with the respective said months, and means to accumulate, through cycles of seven, the sum of those code numbers corresponding to a date selected from the four said members, an additional code number on the said first one of said members associated with each of the year numbers divisible by 4, and means to permit the viewing of said additional code number only in the case of a date involving January or February.

6. A calendar device comprising a plurality of circular members arranged for rotation about a common center, a first one of said members bearing the year numbers 00 to 99 arranged in numerical order at a fixed radial distance and code numbers arranged in correspondence with the respective said year numbers, a second one of said members bearing century numbers arranged in numerical order at a fixed, radial distance and code numbers arranged in correspondence with the respective, said century numbers, a third one of said members bearing the day-of-the-month numbers 1 to 31 arranged in numerical order at a fixed, radial distance and code numbers arranged in correspondence with the respective, said day-of-the-month numbers, a fourth one of said members bearing the names of the months, in order, at a fixed, radial distance and code numbers arranged in correspondence with the respective said months, and means to accumulate, through cycles of seven, the sum of those code numbers corresponding to a date selected from the four said members, an additional code number on the said first one of said members associated with each of the year numbers divisible by 4, except the year 00, a further code number associated with the year 00, means to permit the viewing of said additional code numbers and said further code number only in the case of a date involving January or February, and means to permit the viewing of said further code number only in the case of a date involving a century number divisible by 4.

7. A calendar device comprising a series of circular members rotatable about a common center, the first of said members comprising a first disk with raised annulus, a second disk nested in said first member, and having an outer, raised annulus and two inner, raised annuli, defining an outer, annular trough, an inner, annular trough, and a central, circular, dished portion, annular members nested in said respective troughs, and a third disk nested in said dished portion, said first disk bearing the year numbers 00 to 99 arranged in numerical order on the raised annulus, and code numbers arranged in correspondence with the respective, said year numbers, said second disk bearing century numbers on its raised annulus, arranged in numerical order, and code numbers arranged in correspondence with the respective, said century numbers, the annular member in said outer trough bearing the day-of-the-month numbers, 1 to 31, arranged in numerical order, and code numbers arranged in correspondence with the said day-of-the-month numbers, the annular member in said inner trough bearing the names of the months, in order, and code numbers arranged in correspondence with the respective, said names of the months, said third disk having seven equidistant stations for stepwise rotation and bearing the names of the days of the week in association with said stations, masking means for said device provided with

5 apertures for viewing the selected components of a given date as arranged by rotation of said disks and annuli, further apertures for viewing the code numbers corresponding to the selected date components, and an aperture for viewing the corresponding day of the week as selected by dialing said third disk in accordance with the code numbers in view.

8. A calendar device comprising a series of circular members rotatable about a common center, the first of said members comprising a first disk with raised annulus, a second disk nested in said first member, and having an outer, raised annulus and two inner, raised annuli, defining an outer, annular trough, an inner, annular trough, and a central, circular dished portion, annular members nested in said respective troughs, and a third disk nested in said dished portion, said first disk bearing the year numbers 00 to 99 arranged in numerical order on the raised annulus, and code numbers arranged in correspondence with the respective, said year numbers, said second disk bearing century numbers on its raised annulus, arranged in numerical order, and code numbers arranged in correspondence with the respective, said century numbers, the annular member in said outer trough bearing the day-of-the-month numbers, 1 to 31, arranged in numerical order, and code numbers arranged in correspondence with the said day-of-the-month numbers, the annular member in said inner trough bearing the names of the months, in order, and code numbers arranged in correspondence with the respective, said names of the months, said third disk having seven equidistant stations for stepwise rotation and bearing the names of the days of the week in association with said stations, masking means for said device provided with apertures for viewing the selected components of a given date as arranged by rotation of said disks and annuli, further apertures for viewing the code numbers corresponding to the selected date components, and an aperture for viewing the corresponding day of the week as selected by dialing said third disk in accordance with the code numbers in view, the code numbers for the year numbers divisible by four being arranged beneath said inner trough for coaction with the month data, with the code number for the year 00 dissociated from the balance of the year code numbers, said masking means having viewing means for said year code numbers, said second disk having a sector slot for viewing said year code numbers and a series of apertures arranged for alignment with said year 00 code number when the selected date involves a century number divisible by four, and said annular member in said inner trough having an aperture arranged to provide for viewing any of said year code numbers when the date involves January or February.
